Primary Examiner — Rhea Shields(74) *Attorney, Agent, or Firm* — Knobbe Martens Olson & Bear LLP(57) **CLAIM**

The ornamental design for a medical treatment cart, as shown and described.

DESCRIPTION

FIG. 1 is a left front top perspective view of a medical treatment cart, showing our new design.

FIG. 2 is a top plan view thereof.

FIG. 3 is a bottom plan view thereof.

FIG. 4 is a right side view thereof.

FIG. 5 is a left side view thereof.

FIG. 6 is a front view thereof; and,

FIG. 7 is a rear view thereof.

In the drawings, the broken lines illustrate features of the medical treatment cart that forms no part of the claimed design.
